(57) **CLAIM**

The ornamental design for an excavator, as shown and described.

DESCRIPTION

FIG. 1 is a rear, left-side, and top view of an excavator, showing the new design.

FIG. 2 is a right-side elevation view of the excavator.

FIG. 3 is a top plan view of the excavator.

FIG. 4 is an enlarged rear elevation view of the excavator.

FIG. 5 is an enlarged front elevation view of the excavator.

FIG. 6 is a left-side elevation view of the excavator; and,

FIG. 7 is a bottom plan view of the excavator.

The broken lines depict elements of the excavator that do not form part of the claimed design.

1 Claim, 7 Drawing Sheets
